HINGED COVER MOLDED PLASTIC DISPLAY RECEPTACLE

Samuel Braun, Rockville Centre, and Max Crystal, Forest Hills, N. Y., assignors to Braun-Crystal Mfg. Co., Inc., Middle Village, N. Y., a corporation of New York

Application January 23, 1950, Serial No. 7,416

Term of patent 14 years

(Cl. D80—5)

To all whom it may concern:

Be it known that we, Samuel Braun and Max Crystal, both citizens of the United States and residents, respectively, of Rockville Centre, Nassau County, State of New York, and Forest Hills, Queens County, State of New York, have invented a new, original, and ornamental Design for a Hinged Cover Molded Plastic Display Receptacle, of which the following is a specification, reference being had to the accompanying drawings, forming part hereof and in which:

Fig. 1 is a top plan view of a plastic molded receptacle, showing our new design.

Fig. 2 is a bottom plan view thereof.

Fig. 3 is a front end elevational view.

Fig. 4 is a rear elevational view.

Fig. 5 is a side elevational view.

Fig. 6 is a perspective view upon a small scale as compared to Figs. 1 to 5, showing the box in open condition.

We claim:

The ornamental design for a hinged cover molded plastic display receptacle, substantially as shown.

SAMUEL BRAUN.
MAX CRYSTAL.
